UNITED STATES PATENT OFFICE.

THOMSON MAO, OF SWISSVALE, PENNSYLVANIA.

CASH-ACCOUNT REGISTER.

1,335,447.

Specification of Letters Patent. Patented Mar. 30, 1920.

Application filed January 11, 1919. Serial No. 270,706.

To all whom it may concern:

Be it known that I, THOMSON MAO, a citizen of the Republic of China, residing at Swissvale, in the county of Allegheny and State of Pennsylvania, have invented certain new and useful Improvements in Cash-Account Registers, of which the following is a specification, reference being had to the accompanying drawings.

- 10 This invention relates to improved cash account registers, and has, relation more particularly to a device of this general character which is adapted to be attached to a money holder, such as a bill holder, wallet, hand bag, or similar article adapted to hold money for current use, and it is an object of the invention to provide a novel and improved cash account register which may be employed with convenience and facility to 20 keep an account of daily expenses, and whereby the balance of money or the total expenditure relative to certain items may be readily determined without the necessity of an arithmetical operation.
- 25 It is also an object of the invention to provide a novel and improved device of this general character including a pocket adapted to receive a card or the like, and wherein a wall of said pocket is provided with openings or slots to permit notations to be made upon the card or the like within the pocket, and wherein the wall provided with the openings or slot is provided with designations for various items so that a notation 35 relative to each of the various items may be made upon the portions of the card or the like exposed through the openings or slots of the wall of the pocket.

An additional object of the invention is 40 to provide a cash account register having novel and improved means whereby the balance of money on hand or the amount of certain expenditures may be determined with facility and accuracy, and wherein 45 said means comprises a plurality of series, of aligned openings, certain of which represent "cents" and the remainder of which represent "dollars," and with which coact rods or indices insertible through the openings, and wherein said openings and the rods or indices are provided with coacting value indications to effect the desired calculations.

The invention consists in the details of

construction and in the combination and arrangement of the several parts of my improved cash account register whereby certain important advantages are attained and the device rendered simpler, less expensive and otherwise more convenient and advantageous for use, as will be hereinafter more fully set forth:

The novel features of my invention will hereinafter be definitely claimed.

In order that my invention may be the better understood, I will now proceed to describe the same with reference to the accompanying drawings, wherein:

Figure 1 is a view in elevation of a cash account register constructed in accordance with an embodiment of my invention;

Fig. 2 is a view in elevation of one of the rods or indices as herein embodied;

Fig. 3 is a view in side elevation of the rod or index as illustrated in Fig. 2;

Fig. 4 is a view in elevation of the side of the rod or index opposite to that shown in Fig. 2;

Fig. 5 is an enlarged fragmentary sectional view taken substantially on the line 5—5 of Fig. 1;

Fig. 6 is an enlarged fragmentary sectional view taken on the line 6—6 of Fig. 1.

As disclosed in the accompanying drawings, M denotes a money holder which may be a wallet, bill holder or the like, and overlying a wall of said holder M is a sheet 1 preferably substantially opaque, such as celluloid, ivory, metal, card board, or the like. This sheet 1 is stitched or otherwise secured, as at 2, along a longitudinal marginal portion and its end marginal portions to a wall of the holder M, and in the present embodiment of my invention and as particularly illustrated in Fig. 1, the sheet 1 is further secured to the wall of the holder M by a further line of stitching 3 extending transversely of the sheet 1, and in relatively close proximity to an end thereof, and whereby said sheet 1 is divided into two fields X and Y. The field X is provided with a pocket P, which pocket P contacts with the adjacent wall of the holder M to afford a pocket P' into which a card C is adapted to snugly fit.

The field Y is also provided with a plurality of longitudinally disposed slots 4 preferably arranged in two series with the slots of each series longitudinally disposed

but spaced transversely of the sheet 1 and preferably with similar slots of both of the series in longitudinal alignment. It is also preferred that the space 5 between each pair of slots 4 of each series be equal to the width of each of the slots, and for which reason the slots 4 are all of the same width.

As is clearly indicated in Fig. 1, one longitudinal side of the pocket P is open and the field Y of the sheet 1 adjacent said free longitudinal margin is provided with the supplemental slots 6. One of these slots 6 is adapted to afford means whereby a period of time such as a particular month of a year 10 may be written upon the card C when applied within the pocket P, while the second slot 6 is adapted to afford means whereby the money at hand at the beginning of the period may be readily written upon the 15 card C.

The upper marginal portion of the field Y immediately above each of the slots 4 has printed or otherwise arranged thereon the designations 7 of the various items to be recorded or written upon the card C, and the various designations 7 coacting with each of the slots are separated by the lines 8 at right angles to the slot 4 and which lines serve as guides for the proper entry 20 on the inserted card C.

In practice it is preferred that the general designations 7 be arranged at the upper portion of the sheet 1 or field Y, while the details of the various items are arranged 25 on the intermediate spaces 5, and which spaces are provided with the specific designations 9 herein disclosed as certain letters of the alphabet. If preferred, however, these designations 9 may be omitted.

40 In entering an expense, besides the amount, the particular item is to be recorded by referring to the designations 9 so as to enable an exact distribution of the different items while closing the account.

45 For example, should \$5 be spent for clothing on February 1, this amount is recorded on the card under date of February 1 and in the column designated "Dry goods," the letter A being put alongside the figure to 50 show that the money was spent for clothing and not the other items under "Dry goods." If the \$5 had been spent for furniture, the letter C would be used.

55 In the form of my invention as illustrated in Fig. 1, each of the series of slots 4 is five in number, and after said spaces have been filled upon the initial insertion of the card C, said card C is moved laterally a distance equal to the width of a slot 4 so that the 60 unused portions of the card C previously covered, will be brought into sight, and which permits substantially the whole surface of the card C to be used. In practice, it has been found that the card C is frictionally held in either of these two posi-

tions, although when in the second position, the same may be further maintained against slip by pressure of the digits of the hand holding the holder M. When one face of the card C has been substantially filled, the 70 card may be reversed and the opposite face employed.

In practice the designations 7 are of particular importance, as such designations 7 serve to itemize the different accounts so 75 that the distribution of the same may be easily attained. For example, the designation "Exchange" is to be used to record the value of bills each time they are taken out for exchange. This being required at the 80 time of taking out, avoids the mistake of giving a wrong money note of the denomination required. It also serves as a check of the bills on hand. For example, the designation "Exchange" is to be used to record 85

the value of bills. This means that if a ten dollar note is taken out for the payment of five dollars, the fact that a ten dollar note is out is recorded in this column. This gives a record showing how the payment has 90 been made, by cash or otherwise. Should the amount of payment be five dollars and ten dollars is recorded in the "Exchange" column, it is known at once that a bill of ten dollars was used and a balance of five 95 dollars was received. If this balance of five dollars is also a note, the fact can also be recorded. The designation "Petty cash," as a further example, is used to record the amount of small denominations which may 100 be taken from the pocket for the use of small expenses, such as street car fares, newspapers, or the like. However, by an inspection of Fig. 1, it will be noted that provision is made to record these expenditures, together with other expenditures which the user may have to make. In other words, the designation "Petty cash" is to indicate the amount of money which is to be placed outside of the money holder M, as for instance 105 a pocket or other convenient receptacle.

It has also been found desirable to provide the field Y with delineated spaces 10 for the insertion of the name and address of the owner, together with further delineated spaces 11 whereby record may be made 115 of whom to report in case of accident.

While a suitable implement, preferably a pencil, may be employed for writing the various items, a sheet of carbon, if desired, may be properly disposed over the writing surface of the card C and the point of the rod or index R, to be hereinafter more particularly referred to, may be employed to effect the desired record.

120 It is also to be understood that if desired the card C may have produced thereon the designations similar to the designations 7, and in the same relative arrangement, but as this is believed to be obvious, a detailed 125 130

description and illustration is thought to be unnecessary.

As is illustrated in Fig. 1, a marginal portion of the holder M has suitably affixed thereto a sleeve 12 with which is adapted to be engaged a writing implement W, preferably a pencil, and which member W has secured to its butt end a flexible member 14 also suitably secured to the holder M so that 10 said implement W will be held against accidental displacement or loss.

The field X of the sheet 1 is provided with a plurality of series of transversely disposed openings 15 with the openings of 15 each series in alignment. As is particularly illustrated in Fig. 1, two series of openings 15 are arranged at opposite sides of a heavy transversely disposed line 16 with the openings 15 at the right of the line 16 identified 20 as "cents" and the openings 15 at the left of the line 16 being identified as "dollars". It is to be understood that if desired more than two series of openings 15 may be provided at the left of the line 16, but only two 25 series are disclosed in Fig. 1, because it is customary to pay amounts in excess of one hundred dollars by check.

As is particularly illustrated by Fig. 1, each series of openings 15 are nineteen in 30 number, and corresponding openings of each of the series are aligned longitudinally of the holder M. The central openings 15 of the series are intersected by a heavy line 17 directed longitudinally of the holder M, or 35 more particularly the sheet 1. The opposite end portions of the line 17 are provided with an identity 18, herein disclosed as "0". The remaining corresponding openings 15 of the several series are intersected by the 40 lines 19 and the opposite end portions of the lines 19 are provided with the valuations 20 arranged consecutively from "1" to "9", with the lower numeral above the line 17 immediately adjacent said line and with 45 the highest number of the valuations 20 below the line 17 immediately adjacent said line 17.

Each of the openings 15 is of a diameter to permit the ready insertion therethrough 50 of a rod or index R, and in practice there is a rod or index R for each series of openings 15.

Each rod or index R, and as particularly illustrated in Figs. 2, 3, and 4, includes a 55 flat body or shank 21 provided at one end with a returned portion or wing 22 which is adapted to overlie the outer surface of the field X when the rod or index R is in a 60 applied position and, in practice, the flat face of the body or shank 21, which the returned portion or wing 22 overlies, is termed the front face.

The front face of the body or shank of 65 each of the rods or indices is provided with the graduations 23 equidistantly spaced,

with the space between each of the graduations 23 equal to the space between the centers of an adjacent pair of openings 15 of a single series. The uppermost graduation 23 is spaced from the upper or adjacent end 70 of the shank or body 21 a distance equal to the distance between adjacent graduations 23. The opposite end portion of the body or shank 21 is provided with a point 24 of a length substantially equal to the distance 75 between adjacent graduations 23.

The opposite or rear face of the body or shank 21 is provided with the graduations 25 spaced apart as has been just described, relative to the graduations 23, but the 80 graduations 25 are ten in number running consecutively from "0" to "9" with "0" adjacent the top end of the shank or body 21, and spaced from said top end a distance substantially equal to the distance between 85 a pair of adjacent graduations 25. The 90 graduations 23 run consecutively from "1" to "9", with the highest number at the upper end of the body or shank 21 or adjacent that end provided with the return portion 95 or wing 22. In other words, the graduations 23 and 25 are reversely identified. It is also preferred that the identifying numerals 26 and 27 coating, respectively, with the 100 graduations 23 and 25, be differently colored, as for instance the numerals 26 red and the numerals 27 black. It is also preferred that the return portion or wing 22 be painted a prominent color, preferably red. To use the calculating or registering feature, the amount of money at hand at the beginning of the entry is indicated by inserting the rods or indices R into the openings 15 of the series bearing the required 105 numbers. As indicated in Fig. 1 of the drawings, the amount of money on hand is \$32.65. In employing the calculator or register, it is important that the openings 15 above the line 17 be used.

Each time a certain amount of money is 110 spent, the rod or index is moved upward to expose at the opening 15 through which it is directed the number similar to the amount applicable to that column and then it is observed through which opening 15 the point 115 or tip 24 is exposed. The rod or index R is then taken out and reinserted through said opening. In other words, should an expenditure be made of \$2.15, from the amount \$32.65 on hand as shown the rod 120 or index R coating with the outer column of cents will be moved longitudinally until the graduation 23 on the front face of the rod 125 is arranged at the opening through which the rod or index is inserted. When in this position the point or tip 24 will be exposed through the opening 15 of that particular series which is identified by "0". The rod or index is then completely removed and reinserted through this last iden- 130

tified opening. The index or rod R coacting with the inner or "tens" column at the right of the line 16 is then longitudinally moved until the graduation "1" is exposed through the opening through which said rod or index is inserted, and when in such position the point or tip 24 of the rod or index will be exposed through the opening 15 of the series identified by "5".

10 The rod or index R coacting with the "units" series of openings 15 at the "dollars" or left side of the line 16 is then longitudinally adjusted until the number "2" of said rod or index is exposed through the opening 15 of such series through which the rod or index is inserted. When so arranged the tip or point 24 of the rod or index will be exposed through the opening in such series identified by "0". The rod or index will then be inserted through this opening, and the resultant reading of all of the rods or indices will show that there is a balance of \$30.50. It is to be noted that should the amount expended be in the tens of dollars, the point or index coacting with the "tens" column of dollars would be similarly adjusted.

In the event that the tip or rod 24 of any one of the rods or indices R should point to a hole 15 that is below the horizontal line 17, such rod or index is inserted through a similarly identified opening in the same series above the line 17, and the rod or index R coacting with the series or column to the left is moved down one hole. In other words, should an expenditure be made of \$4.27 from the amount \$32.65 on hand as shown, the index or rod R coacting with the outer series of openings 15 to the right of the line 16 will be longitudinally adjusted until the numeral "7" of said rod or index is exposed through the opening through which said rod or index is inserted, and which adjustment will result in the point or tip 24 being exposed through the opening identified by "8" below the line 17. The rod or index is then removed and inserted through the opening identified as "8" above the line 17, and the rod or index R coacting with the inner series or column of openings at the right of the line 16 is inserted through the opening 15 immediately below, or in other words through the opening identified as "5" above the line 17. This second rod or index is then longitudinally adjusted until the numeral "2" is exposed through the opening in which the rod or index is inserted, and which results in the tip or point 24 of said rod or index being exposed through the opening 15 being identified as "3". The rod or index R is then inserted through this opening. The rod or index R coacting with the "unit" series or column of openings 15 at the left of the line 16 is then longitudinally adjusted until the nu-

meral "4" carried thereby is exposed through the opening through which the rod or index is inserted, and which will result in the tip or point 24 of said rod or index being exposed through the opening being identified as "8" below the line 17. This rod or index R is then inserted through the opening identified as "8" above the line 17, and the rod or index R coacting with the "tens" series or column of openings 15 is moved down one opening, so that the balance of money on hand will read \$28.38.

In finding the total expenditures of different items, all of the rods or indices R are removed and worked upside down in the holes below the line 17.

As an example, should it be necessary to add the figures \$5.68 and \$6.79, remove all the rods or indices R from the openings and insert three rods or indices in the openings below the line 17 and identified by the "Dollar" and "Cent" designations and as identified by the designation 20, i.e., one rod in opening below line 17 identified by units of dollars and the figure 5, one rod in the tens of cents column and identified by the figure 6, and the third rod in the units of cents column and identified by the figure 8. The rods or indices are inserted in these openings upside down, that is, the tips 24 point upwardly instead of downwardly. To add the sum of \$6.79, move the rod in the opening identified by figure 5 until the figure 6 marked on the rod is aligned with the line 19 identified by the figure 5. The tip 24 of this rod will point to an opening above the line 17 identified by figure 1. Now insert the fourth rod in the openings below the line 17 and identified by the tens of dollars column and the figure 1, move the rod in the units of dollars column to the opening below line 17 and identified by the figure 1. This shows that \$5 plus \$6 is \$11. The same procedure applies to the other figures.

The total expenditures within a given period of time may also be determined without the reversal of the rods or indices R. With the rods or indices in a position to indicate the balance of money on hand at present, the numerals 26 on said rods or indices exposed through the openings 15 below the line 17 which are identified by the valuations 20 as the balance of money on hand at the beginning of the period will show the total amount of expenditures between these two periods. In other words, if the money on hand one month ago was \$58.79, the expenditures for the month will be found as follows, the present balance on hand being \$32.65 as shown: In the series of openings 15 indicated as "units" of cents, the numeral "4" of the rod or index R will be exposed through the opening 15 below the line 17 identified by the valuation 20 and

- which will indicate the "unit" of cents of the expenditure. Through the opening 15 of the "tens" of cents series and identified by the numeral "7," the numeral "1" on the rod or index R will be exposed to indicate the "tens" of cents of expenditures. Similarly through the two openings 15 of the dollar series identified by the numerals "5" and "8," the numerals "2" and "6" 10 of the coacting rods or indices R respectively, will be exposed so that the total amount of expenditures will be indicated as \$26.14. In case a rod or index is not exposed through an opening 15 below the line 15 17 as identified by the balance on hand at the beginning of the period, because said rod or index is drawn too far up, move the rod or index R to the left of the series under consideration one space up, *i. e.* make the numeral "9" on the rod or index R even with the line 19 intersecting the opening 15 through which the rod is inserted, and then 20 read the figure on the rod through the opening identified as the balance of money at the beginning of the period but above the line 17. This figure on the rod or index R will give the amount of expenditures. In other words, if the amount of money at hand twenty days ago was \$41.09, the expenditures 25 during these twenty days will be found as follows the present balance on hand being \$32.65 as shown: Along the series of "units" of cents find the opening below the line 17 that is identified by the numeral 30 "9." The numeral "4" on the rod or index R will be exposed through such opening. In the series of openings 15 for "tens" of cents find the opening identified by the numeral "0." It is to be noted this time that 35 no such opening is provided below the line 17. Therefore move the rod or index R to the left of that series of openings 15 or of the series of "units" of dollars, up one space to bring the numeral "9" on the rod or index R for exposure through the opening 40 15 intersected by the line 19 identified by the valuation "2." Through the opening of the column of "tens" of cents identified by the numeral "0" on the line 17, the numeral 45 "4" on the rod or index R will be exposed. The expenditures of that period in "cents" will therefore be 44. In the series of openings 15 of "units" of dollars with the rod or index one space up locate the 50 opening 15 identified by the numeral "1." The rod or index is again out of sight. Similarly, move the rod or index R in the series of tens of dollars one space up to bring the numeral "9" on the rod or index 55 R for exposure through the opening 15 intersected by the line 19 identified by the valuation 3. The numeral "8" on the rod or index R will then be exposed through the opening 15 above the line 17 identified by 60 the valuation "1". In the column of "tens" 65 of dollars, with the coacting rod or index one space up, it will be found that the tip 24 of the rod is seen through the opening below the line 17 and identified by the valuation "4," that indicates that no "tens" of 70 dollars has been spent, as the tip 24 gives "0" value. The total amount of expenditures during these twenty days is therefore \$8.44.
- If the balance on hand at the beginning 75 of a period is an even number, such as \$100, the present balance on hand being \$32.65 as shown, expenditures will read through the openings 15 below the line 17 in the first three series representing "tens" and 80 "units" of dollars, and the "tens" place of cents intersected by the line 19 identified by the valuation 9 and the last figure through the opening of the series of "units" of cents intersected by the heavy line 17. For 85 instance, if the amount of money two months ago was \$100, the total expenditures will be \$67.35, the first three figures reading from the openings immediately below the line 17 and the last one on the line 17. 90
- It will be understood that should it be desired to have my improved calculating or registering device operate to determine the amount expended instead of the balance, it is only necessary to reverse the order of 95 the numerals 20 with the operation the same as has been hereinbefore described.
- From the foregoing description, it is thought to be obvious that a cash account register constructed in accordance with my 100 invention is particularly well adapted for use by reason of the convenience and facility with which it may be assembled and operated, and it will also be obvious that my invention is susceptible of some change and 105 modification without departing from the principles and spirit thereof, and for this reason I do not wish to be understood as limiting myself to the precise arrangement and formation of the several parts herein 110 shown in carrying out my invention in practice except as hereinafter claimed.
- I claim:
- A cash registering device comprising a member provided with a plurality of series 115 of openings arranged in columns, means on said body for separating said columns into dollars and cents, the central openings of all of the columns being indicated as "0," and the openings of each of the series above 120 the "0" opening being consecutively numbered from "1" to "9" with the smaller number adjacent the "0" opening, the openings of each series below the "0" opening being also consecutively numbered from "1" 125 to "9," with the highest number adjacent the "0" opening, and a rod coacting with each of the series and insertible through the openings thereof, said rod having one face provided with graduations numbered con- 130

6
secutively from "1" to "9," said graduations being equidistantly spaced with adjacent graduations spaced a distance substantially equal to the space between the centers of adjacent openings, the graduation "9" being adjacent the top of the rod, and spaced from said top a distance substantially equal to the space between adjacent

graduations, the upper end portion of the rod having an overlying wing.

10

In testimony whereof I hereunto affix my signature in the presence of two witnesses.
